UNITED STATES PATENT OFFICE.

GUSTAV MILSE, OF BREMEN, GERMANY, ASSIGNOR TO EMIL ZIMMERMANN, OF NEW YORK, N. Y.

EXCHANGEABLE INDIA-RUBBER HEEL.

Application filed April 19, 1921. Serial No. 462,778.

To all whom it may concern:

Be it known that I, GUSTAV MILSE, a citizen of the German Republic, residing at Bremen, Germany, have invented certain new and useful Improvements in Exchangeable India-Rubber Heels, of which the following is a specification.

This invention relates to exchangeable rubber heels.

10 The novelty in the present instance resides in the particular construction of the heel, as more fully hereinafter shown and described.

15 The invention is clearly illustrated in the accompanying drawings, in which:

Figure 1 is a vertical section of the heel of a shoe showing my improvement applied.

Figure 2 is an under plan of the latter.

20 Figure 3 is an elevation of the fastening device.

Figure 4 is an enlarged section through the vulcanized lift.

25 Like letters of reference indicate like parts throughout the several views.

Referring to the drawings:

b designates a heel to which the heel lift is attachable.

30 *a* is the heel lift of india-rubber within which is a plate *c* of metal formed with the holes *h* around which are the struck-up burrs *i*, see Figure 4, and the whole is

vulcanized in the rubber plate as seen in Figure 1. The burrs *i* curl over at their edges, as seen in Figure 4, so as to provide 35 a secure hold in the rubber and prevent their being pulled out.

f are hollow longitudinally slotted members conical in form adapted to be driven into the heel *b* and into which are adapted 40 to be forced the metallic conical fastening members *d*, as seen in Figures 1 and 3. The driving in of the members *d* will spread the sections of the members *f* and cause a firm locking of the parts. The members 45 *d* are formed with collars *g* which prevent them from being pulled out of the lift *a* in which they are embedded.

What is claimed as new is:—

A lift, metallic conical headed fastening 50 members having their heads molded in said lift, and hollow longitudinally slotted members coaxial in form and adapted to be driven into a member and to receive and be spread by said fastening members said 55 members having collars to prevent them from being pulled out of the lift in which they are embedded.

In testimony whereof I affix my signature in presence of two witnesses.

GUSTAV MILSE.
